CLAIM

The ornamental design for a faucet, as shown and described.

DESCRIPTION

FIG. 1 is a left, top, front perspective view of a plumbing faucet embodying my new design;

FIG. 2 is a left side elevational view thereof, the right side elevational view being a mirror image of the left side shown;

FIG. 3 is a front elevational view thereof;

FIG. 4 is a rear elevational view thereof;

FIG. 5 is a top plan view thereof; and,

FIG. 6 is a bottom plan view thereof.

The broken line representations of holes in FIGS. 1-3, and of an inner wall in FIG. 6, are for the purpose of illustration only, and form no part of the claimed design.

The characteristic feature of my design resides in shroud-like rounded transition between the top of the faucet body and the sides of the faucet body.
